(57) **CLAIM**

The ornamental design for a cat litter box, as shown and described.

DESCRIPTION

FIG. 1 is a front, right, and top perspective view of a cat litter box, showing our new design;

FIG. 2 is a rear, right, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a detailed view taken from encircled portion labeled "9" in FIG. 2;

FIG. 10 is a detailed view taken from encircled portion labeled "10" in FIG. 1;

FIG. 11 is a detailed view taken from encircled portion labeled "11" in FIG. 3; and,

FIG. 12 is a detailed view taken from encircled portion labeled "12" in FIG. 5.

The short-dash and long-dash broken lines in FIGS. 1-3, 5, and 9-12 denote the boundaries of the detail areas and form no part of the claimed design. The even broken lines in the drawings are portions of the cat litter box that form no part of the claimed design.
